UNITED STATES PATENT OFFICE.

SIDNEY A. RAGAN, OF NEW ORLEANS, LOUISIANA, ASSIGNOR OF ONE-HALF TO
HAROLD FROST, OF NEW ORLEANS, LOUISIANA.

PAPER-PERFORATING MACHINE.

Application filed May 16, 1924. Serial No. 713,751.

To all whom it may concern:

Be it known that I, SIDNEY A. RAGAN, a citizen of the United States, residing at New Orleans, in the parish of Orleans and 5 State of Louisiana, have invented certain new and useful Improvements in Paper-Perforating Machines, of which the following is a specification.

This invention relates to paper perforating machines, and it consists in the novel features hereinafter described and claimed.

An object of the invention is to provide a machine in the form of an attachment, adapted to be used in conjunction with a 15 piano, organ, or other keyed instrument for perforating music sheet paper, adapted to be used upon automatic pianos.

A further object of the invention is to provide in a machine of the character stated, means for accurately recording the playing of the performer, in exact coincidence with the depression of the keys of the instrument when the music is played upon the automatic piano.

25 In the accompanying drawings, forming a part of this specification:

Figure 1 is a plan view of the paper perforating machine.

Figure 2 is a side elevation of the same.

30 Figure 3 is a transverse sectional view of the same.

Figure 4 is a fragmentary perspective view thereof.

Figure 5 is a fragmentary side elevation 35 of a piano key action, indicating the manner in which the perforating machine is connected with the key.

As illustrated in the accompanying drawings, the perforating machine comprises a 40 frame 1, having a shaft 1' journaled thereon. A counter-balance wheel 2 is mounted upon the shaft 1. Guides 3 are mounted upon the vertical sides of the frame 1. A bar 4 is disposed transversely of the frame 1, and may move vertically thereon. Vertically disposed punch bars 5, are slidably carried by the bar 4. Each bar 5 is provided at one side with a notch 5'. Latch strips 6 are mounted for horizontal movement, in the bar 4, and are disposed at right angles to the rods 5. The latches 6 may enter the notches 5' of the rods 5. A wire 6' is connected at one end with each of the latch strips 6, and is trained around cylindrical guide rods 7' and connected with a

coil spring 8'. The spring 8' is connected with a rocker 9', and a wire 10' connects the rocker with the key 11' of the instrument. Eccentrics 8 are mounted upon the end portions of the shaft 1' and eccentric bands 12' pass around the peripheries of the eccentrics and are operatively connected with the end portions of the bar 4. The bars 5 are pointed, at their lower ends, as at 13', and the lower portions pass through a guide 9', which is disposed transversely across the frame 1. Springs 10 are secured by clamp bars 11, which extend transversely across the frame 1, and the inner ends of the springs 10 are connected with the punch bars 5. The springs are under tension, with a tendency to normally hold the upper ends of the bars 5, in contact with the lower edge of a stop strip 12, which extends transversely across the frame 1. Springs 13 are 70 connected at their lower ends with the latches 6, and at their upper ends with a cross bar 14', and the said springs serve to move the ends of the bars 6 out of engagement with the notches 5', in the sides of 80 the bars 5. Guides 14 are mounted upon the floor of the frame 1, at the opposite sides of the paper receiving heads thereof. The paper compressing rollers 16 are journaled at the receiving edge of the frame 1. 85 Compression rollers 16 are journaled at the intermediate portion of the frame 1, and bear against the upper surface of the strip of paper, and hold the same in position over a guide plate 17, which extends 90 transversely across the frame 1. Feed rollers 18 are journaled at the opposite edge of the frame 1, from that edge at which the rollers 15 are journaled, and the strip of paper passes between the said feed rollers. 95 A shaft 19 is operatively connected, at one end, with the shaft 1', and is operatively connected at its other end with the shaft of one of the rollers 18. The operating connection between the shaft 19 and the shaft 1' and the shaft of the roller, are in the form of the usual worm and worm wheel gears.

The shaft 1' is rotated continuously by a belt, which is passed around the belt pulley 7, mounted upon the said shaft. Through the operative connection of the eccentric 8 and the eccentric bands 9, the bar 4 is reciprocated vertically between the guides 3. At the same time, rotary movement is trans- 110

mitted from the shaft 1', through the shaft 19, to one of the rollers 18 and the strip of paper, which is passed between the said rollers 18 is moved longitudinally across the frame 1 and the guide pulley 17. When the piano key 11' is depressed, the wire 10' is moved longitudinally, whereby the rocker 9' is swung and the wire 6' is moved longitudinally and around the rod 7', whereby the connected bar 6 is moved longitudinally against the tension of the attached spring 13, and the end of the rod 6 enters the notch 5' of one of the punch bars 5. Thus, the said punch bar is fixed with relation to the bar 4, and the pointed end 13' is projected through the strip of paper producing a perforation therein. The same action takes place, when all of the succeeding keys 11' are struck or depressed, and thus the necessary perforations are provided in the strip or sheet of paper. When the key 11' raises, the wires 10' and 6' are moved in an opposite direction, whereby the spring 13 withdraws the bar 6 from the notch 5' of the punch bar 5, and the springs 10 raise the punch bar 5, until its upper end comes in contact with the stop 12.

Having described the invention, what is claimed is:

30 1. A paper perforating machine, comprising a frame, a guide plate mounted thereon, means for guiding a strip of paper across the guide plate, a bar movably mounted upon the frame above the guide plate, means for reciprocating said bar vertically; a punch bar movably mounted in the first mentioned bar, spring means for normally holding the punch bar in an elevated position, a spring pressed bar mounted for movement transversely of the first mentioned bar and adapted to engage the punch bar, and means operatively connecting the spring pressed bar, with the key of an instrument.

45 2. An attachment for a musical instrument of the class described comprising a frame including a base over which the paper to be perforated is adapted to pass, a vertically movable horizontally disposed bar mounted for movement upon said frame, a

paper punching bar slidably mounted upon 50 said vertically movable bar, latches also carried by said vertically movable bar, said latches being adapted to connect said punching bar to the first named bar for movement therewith, and a key operated connection 55 for operating said latches.

3. In an attachment of the class described, a frame comprising a base, end walls rising therefrom, vertical guides carried by said walls, a horizontal bar extending between said walls and having its ends vertically 60 slidable in said guides, a plurality of punch bars slidably mounted for movement with or relative to said first named bar, said base being provided with openings below said punch bars for selective reception of the lower ends of the latter, spring means for normally maintaining said punch bars in a predetermined position, latch strips slidable upon the first named bar and cooperative 65 with the punch bars for coupling the punch bars to the vertically movable bar for movement therewith, and key operated means connected to the latch strips for operating them.

4. In an attachment of the class described, a frame embodying a base and walls at the opposite ends thereof, said base being provided with apertures across which the paper is adapted to move, means in association with said base for feeding the paper across it and maintaining it in a taut condition, a horizontally disposed bar mounted for vertical movement between the end walls, a guide mounted between said walls 85 beneath said movable bar, punch bars mounted upon the movable bar and having their lower ends extending through said guides and adapted to be selectively projected through the aforesaid apertures, 90 spring means for maintaining the punch bars in a predetermined position, latch members carried by said first named bar and engageable with said punch bars for coupling the latter to the first bar, and key controlled 95 means for operating said latch members.

In testimony whereof I affix my signature.

SIDNEY A. RAGAN.
